UNITED STATES PATENT OFFICE.

SETH A. CRONE, OF EAST ORANGE, NEW JERSEY.

RAILWAY BRAKE-BEAM.

No. 902,055.

Specification of Letters Patent.

Patented Oct. 27, 1908.

Application filed August 5, 1908. Serial No. 447,022.

To all whom it may concern:

Be it known that I, SETH A. CRONE, a citizen of the United States, and a resident of East Orange, in the county of Essex and 5 State of New Jersey, have invented certain new and useful Improvements in Railway Brake-Beams, of which the following is a specification.

The invention relates to improvements in 10 railway brake-beams, and it consists in the novel beam hereinafter described, and particularly pointed out in the claims.

The object of my invention is, more particularly, to provide an improved and highly efficient compression member for trussed brake-beams, and more especially to construct said member from a structural beam section, preferably of T-shape in cross-section, in such manner that at its end portions it will form 20 recesses for the end portions of the truss-rod, receive the bearing-sleeves for the brake-heads and afford maximum strength to resist the power applied against said end portions in service.

25 The invention will be fully understood from the detailed description hereinafter presented, reference being had to the accompanying drawings, in which:

Figure 1 is an elevation of one end portion 30 of a trussed brake-beam, with the bearing-sleeve thereon for the brake-head, not shown; Fig. 2 is a like view of one end portion of the compression member of the beam, the truss rod and bearing sleeve being omitted; Fig. 3 35 is a transverse section through the compression member and truss rod of the beam on the dotted line 3—3 of Fig. 1; Fig. 4 is a like section through the beam on the dotted line 4—4 of Fig. 1; Fig. 5 is a like section through 40 the beam on the dotted line 5—5 of Fig. 1; Fig. 6 is a like section through the same on the dotted line 6—6 of Fig. 1, and Fig. 7 is a like section through a modified form of the compression member on the line of the section of 45 Fig. 4, this modification consisting in upsetting the web of the beam in lieu of splitting it to straddle the truss-rod in the manner shown in Fig. 4.

In the drawings, 10 designates the compression member, 11 the truss-rod, and 12 the sleeve securing the corresponding ends of said compression member and rod together and adapted to receive, in a well understood manner, the brake-head, not shown.

5 The truss-rod 11 is commonly used in trussed brake-beams and requires no detailed

description; it is customarily threaded at its ends to receive securing nuts 13 which bind against the outer oblique ends of the sleeves 12.

60 The compression member 10 is preferably made from a rolled commercial beam of T-shape in cross-section, and in the production of the member 10 therefrom I do not necessarily modify the beam section except at its 65 end portions, which I do reconstruct in respect to the web 14 and flange 15.

65 My invention resides, therefore, in a novel construction of the end portions of the 70 brake-beam, and in carrying out one form of my invention I split the web 14 to create lips 16 (Fig. 4) which receive between them portions of the rod 11, and outwardly beyond the lips 16 I compress the web 14 and flange 15 into a solid end 17, which outwardly beyond the lips 16 is recessed, as at 18, to continue the recess for the truss-rod 11. In the 75 formation of the solid ends 17 I preserve the general longitudinal plane of the outer central line of the flange 15, as denoted in Figs. 80 1 and 2, and crowd the side portions of the flange 15 in a direction toward the web 14 and press the web in line with its edge in a direction toward the middle of said flange, whereby a solid integral end 17 is produced 85 which has a straight outer edge, diverging sides and a concave inclined inner surface 18, said end decreasing in thickness from about the outer ends of the lips 16 to the outer end of the beam, as shown by the relative thicknesses of metal in the end 17 represented in 90 Figs. 5 and 6.

95 My purpose is to produce solid ends 17 at the end portions of a rolled flanged commercial section and to maintain in said ends the maximum amount of metal disposed to secure the greatest amount of strength and efficiency. I therefore seek to avoid cutting away portions of the beam in creating the compressed ends 17 but find that in the use 100 of some rolled sections it is necessary to clip off a portion of the outer end of the web 14, outwardly beyond that part used in forming the lips 16, prior to the compression of said ends so that I may not have too much metal 105 to be conveniently confined within the sleeve 12, whose diameter is limited to the requirements of standard brake-heads. The lips 16 are formed to preserve or leave in the beam the maximum quantity of metal at the inclined end portions of the rod 11 rather than to afford seats or recesses for said rod, and in 110

22
lieu of forming the lips 16 the same metal may be left in the beam by upsetting the web thereof in the manner shown in Fig. 7, said web being upset in a direction toward 5 the flange of the beam and thereby thickened in affording space for the inclined end portions of the rod 11.

In both the constructions shown in Figs. 4 and 7, the metal of the web is displaced to allow the rod 11, at its ends, to take the proper 10 angular relation to the beam, so that the maximum strength may be secured in the beam. The sleeve 12 is of customary character with the exception that its interior 15 socket conforms to the new shape of the end 17.

What I claim as my invention and desire to secure by Letters Patent, is:

1. In a brake-beam, a rolled flanged compression member having, at each end, the 20 web and side portions of the flange, compressed into a solid integral end forming a recess for the end of the truss-rod; substantially as set forth.

25 2. In a brake-beam, a rolled flanged compression member having, at each end, the web and side portions of the flange compressed into a solid integral end having diverging sides and a concave recess between 30 said sides for the truss-rod; substantially as set forth.

3. In a brake-beam, a rolled flanged compression member having, at each end, the web and side portions of the flange compressed 35 into a solid integral end forming a recess for the end of the truss-rod, and the web of said member inwardly from said ends

being displaced to allow the ends of the rod to have their proper inclination; substantially as set forth. 40

4. In a brake-beam, a rolled flanged compression member having, at each end, the web and side portions of the flange compressed into a solid integral end having diverging sides and a concave recess between 45 said sides for the truss-rod, and the web of said member inwardly from said ends being displaced to allow the ends of the rod to have their proper inclination; substantially as set forth. 50

5. In a brake-beam, a rolled flanged compression member having, at each end, a portion of the web split and spread open to receive the truss-rod, and beyond the same having the web and side portions of the 55 flange compressed into a solid integral end forming a recess for the outer portion of the truss-rod; substantially as set forth.

6. In a brake-beam, a rolled flanged compression member having, at each end, a portion of the web split and spread open to receive the truss-rod, and beyond the same having the web and side portions of the flange compressed into a solid integral end having diverging sides and a concave recess 60 between said sides for the truss-rod; substantially as set forth. 65

Signed at New York city, in the county of New York and State of New York, this fourth day of August A. D. 1908.

SETH A. CRONE.
